DESIGN FOR A BRACKET FOR A MAP OR SIMILAR ARTICLE

Archibald E. MacQuarrie, Minneapolis, Minn.

Application September 7, 1937, Serial No. 71,495

Term of patent 14 years

To all whom it may concern:

Be it known that I, Archibald E. MacQuarrie, a citizen of the United States, residing at Minneapolis, in the county of Hennepin and State of Minnesota, have invented a new, original, and ornamental Design for a Bracket for a Map or Similar Article, of which the following is a specification, reference being had to the accompanying drawing, forming part thereof.

The figure is a perspective view of a bracket for a map or similar article showing my new design.

I claim:—

The ornamental design for a bracket for a map or similar article, as shown.

ARCHIBALD E. MACQUARIE.
